UNITED STATES PATENT OFFICE.

ISAAC E. PALMER, OF MIDDLETOWN, CONNECTICUT.

DESIGN FOR A HAMMOCK.

SPECIFICATION forming part of Design No. 34,333, dated April 2, 1901.

Application filed March 8, 1901. Serial No. 50,397. Term of patent 14 years.

To all whom it may concern:

Be it known that I, ISAAC E. PALMER, a citizen of the United States, and a resident of Middletown, in the county of Middlesex and State of Connecticut, have invented and produced a new and original Design for a Hammock, of which the following is a specification.

The essential features of my design consist in a hammock, provided near its opposite edges with lines of pompons and tassels pendent therefrom, the said lines of pompons extending along lines in proximity to the upper margin of the valance portions.

In the accompanying drawings, Figure 1 is a view of the hammock spread out in a plane, and Fig. 2 is a view of the same in side elevation as it appears when strung or hung for use.

In the accompanying drawings, *a* represents the body; *b*, the valance portion; *c*, the pompons, arranged at intervals along the upper margin of the valance portion, and *d* the tassels pendent from the pompons.

What I claim is—

The design for a hammock, substantially as herein shown and described.

In testimony that I claim the foregoing as my invention I have signed my name, in presence of two witnesses, this 9th day of February, 1901.

ISAAC E. PALMER.

Witnesses:

PAUL S. CARRIER,
CHAS. M. SAUER.
